UNITED STATES PATENT OFFICE.

WALLACE S. AYRES, OF HAZLETON, PENNSYLVANIA.

SEPARATING APPARATUS.

1,094,621.

Specification of Letters Patent. Patented Apr. 28, 1914.

Application filed March 13, 1907. Serial No. 362,171.

To all whom it may concern:

Be it known that I, WALLACE S. AYRES, a citizen of the United States, residing at Hazleton, in the county of Luzerne and 5 State of Pennsylvania, have invented a new and useful Separating Apparatus, of which the following is a specification.

This invention relates to a separating apparatus and is a further development along 10 the line of the apparatus disclosed in my Patent #798,385, issued August 29, 1905.

The machine disclosed in the patent involves in one embodiment of the invention, an endless separating floor which is inclined 15 both longitudinally and transversely, the upper run of the floor being movable in an upward transverse direction. Over this floor, a stream of material such as coal and slate gravitates longitudinally, that portion 20 of the material, as for instance, the coal, whose angle of repose is less than that of the transverse inclination of the table remaining adjacent to the guide which is provided for the stream. As this portion of 25 the material flows along the guide to a coal chute located at the lower end thereof, that portion of the material, to wit, the slate, whose angle of repose is greater than the transverse inclination of the floor will be 30 carried out of the main stream by the upward movement of the floor in a transverse direction, and will be deposited in the slate chute disposed in a position to receive the slate as it drops over the upper longitudinal 35 edge of the floor after its separation from the coal.

The present machine operates upon the underlying principle involved in the above-described separation, but the object of the 40 apparatus is to provide for a more effectual separation by forming a trough, each side of which will operate as an independent separator, so that the slate or the like will be withdrawn from the main stream in opposite directions, thus permitting the employment of a larger stream and effecting a greater separation in a given period of travel of the material.

A further object of the invention is to 45 provide for a series of separations by providing a plurality of troughs, of the charac-

ter above described, in connection with an arrangement of chutes whereby the material carried out of the main stream by one trough will be fed to another at a point 55 removed from the main stream so that while the main stream is subjected to successive separations by successive chutes, the material carried out of the main stream will likewise be successively acted upon so that 60 any coal carried out of the stream with the slate may gravitate back to the main stream; whereas, any slate which has been held in the main stream, while passing over one trough, will be acted upon and removed 65 as the stream passes over one of the succeeding troughs.

To the accomplishment of these objects and others subordinate thereto, the preferred embodiments of the invention reside 70 in those constructions and arrangements of parts to be hereinafter described, illustrated in the accompanying drawings, and succinctly defined in the appended claims.

In said drawings, Figure 1 is a perspective view of a separating apparatus constructed in accordance with my invention, and involving a single trough. Fig. 2 is a diagrammatic view of a slightly different arrangement of the endless belts constituting the trough sections. Fig. 3 is a perspective view showing one arrangement of successive troughs, and Fig. 4 is a similar view showing an arrangement of troughs whereby the material removed from the main 85 stream is subjected to a second separation by a trough located directly below the one to which the material is first fed.

Each part is indicated by the same reference character in all of the views. 90

The primary element of the apparatus is a trough 1 formed by a pair of endless belts 2 and 3 disposed at opposite angles and constituting the side sections of the trough. The belt 2 is passed around inner and outer 95 rotary supports 4 and 5 which may be in the form of rollers, and the belt 3 is passed around similar supports 6 and 7. The two inner rollers 4 and 6 are journaled in standards 8 located at the opposite ends of a 100 base frame 9 which may be of any suitable construction, the general scheme of mount-

ing the belts being similar to that disclosed in my patent above identified. The outer rollers 5 and 7 are journaled in standards 9^a and 10 pivotally connected at their lower 5 ends as indicated at 11 to inclined supporting bars 12, the bars at each end of the apparatus being coaxially connected at their inner ends to the standards 8. Bars 13 are extended between the inner and outer standards 10 and are pivotally connected thereto coaxially with the rollers of the respective sections of the trough. It will be seen that by this arrangement each side section of the trough may be adjusted vertically to vary 15 its transverse inclination, the pivotal connection of the several bars and the standards permitting the necessary changes in their relative angular relation to accommodate this adjustment.

20 While any suitable adjusting means may be provided, I prefer to support the outer end of each bar 12 upon a hand wheel 14 mounted upon an adjusting screw 15 pivoted at its lower end as indicated at 16 to the 25 base 9. It will thus be seen that by rotating the wheels 14 at either side of the trough, one section of the trough may be swung up or down from the inner roller as an axis, so that the upward inclination of 30 the trough sides may be either very steep or very gradual, according to the difference between the angles of repose of the materials to be separated.

The belts 2 and 3 may be driven in any 35 suitable manner, as for instance, by the application of power to a band wheel 17 fixed to the roller 7, the roller 5 being driven from the roller 7 through the medium of a crossed belt 18 passed around pulleys 19 40 fixed to said rollers. It is to be understood, however, that the belts or aprons 2 and 3 may be driven in various other ways, the gearing shown being selected merely for 45 illustrative purposes. Of course, where this character of driving mechanism is employed in practice, a belt tightener of usual construction, not shown, will be employed to take up the slack created in the belt 18 by the relative adjustment of the trough 50 sections.

At the upper outer corner of the section 2 is located the discharge end of a feed chute 20 whereby the material to be separated is fed to the trough. At the lower 55 end of the trough is located a coal chute 21, which may be divided into a middle section 21^a located at the center of the trough, and the side sections 21^b and 21^c located beyond the opposite sides of the middle section to 60 receive different grades of material, it being understood that the coal at the center of the stream will be comparatively pure, but will be more bony in character toward the outer edges of the stream, since the

angle of repose of the latter is somewhat 65 greater than that of the pure coal, although not sufficiently great to allow it to be carried out of the main stream and over the edges of the trough.

Along the outer edges of the trough and 70 in a plane below the same are slate chutes 22, adapted to receive the slate or other material carried upwardly out of the main stream in directions transverse thereto by the outward movement of the trough 75 sections.

Attention is directed to the fact that the two sections of the trough are disposed with their inner edges in overlapping relation. This is considered a particularly desirable 80 feature of the present construction, for the reason that in order to employ endless sections or belts, rotary inner supports must be provided, and if these supports are located in the same horizontal plane, a deep 85 gutter having steep sides would necessarily extend along the entire length of the trough at its center, and as the angles of the sides of this gutter would be much greater than the angle of repose of any portion of the 90 material, no material which reached the gutter, would be carried out of the same by the upward movement of the belts. By arranging the belts in overlapping relation, however, and by feeding the material to the 95 upper section first, said upper section will serve to carry a considerable portion of the slate away from the main stream before the slate drops below the lower edge of said section, and any slate which does, as a matter of fact, reach the extreme bottom of the 100 trough with the coal, will be carried upwardly out of the main stream by the lower section 3, the surface of which is flat to its point of intersection with the under side of 105 the section 2. It is not absolutely necessary, however, that the inner rollers 4 and 6 should be disposed one above another, although this arrangement is perhaps desirable since it facilitates the adjustment of 110 the trough sections. In Fig. 2, for instance, I have shown, diagrammatically, a modified arrangement, which consists in passing the apron 3 around rollers 23 and 24, and in passing the belt or apron 2 around an outer 115 roller 25 and around comparatively small inner rollers 26 and 27, said rollers being quite small, and the roller 26 being located directly above a similar roller 28 located under the upper run of the apron 3 so as to 120 hold said apron in close contact with the under side of the roller 26 for the purpose of preventing any material from passing between the belts.

In Fig. 3 I have shown a plurality of 125 troughs 1^a and 1^b, or what may be termed a multiple trough. Each of these troughs is constructed, operated, and supported, in

substantially the same manner as the trough 1 heretofore described. The trough 1^b, however, is located beyond the lower end of the trough 1^a and in a somewhat lower plane, so that the side chutes 22^a which receive the slate from the outer edges of the trough 1^a may be discharged upon the trough 1^b, adjacent to the upper outer corners thereof. Thus, the trough 1^b will effect a separation similar to that described in connection with a trough 1. The main stream of coal, however, instead of passing to chutes, will pass to the trough 1^b, where it will receive a further separation, the slate which may have been carried with the stream of coal from the trough 1^a being carried outwardly by the sections of the trough 1^b. Furthermore, the slate deposited in the side chutes 22^a from the trough 1^a will be deposited upon the trough 1^b at points removed from the main screen, so that the slate will be caught and carried outwardly before it reaches the main stream, while any coal which may have been deposited in the side troughs 22^a with the slate will gravitate back to the main stream, passing over the trough 1^b. Thus, it will be seen that both the material composing the main stream, and the material removed from the main stream will be subjected to successive separations and these separations may be continued indefinitely by providing additional troughs.

In Fig. 4 I have shown a modified arrangement which consists in disposing troughs 1^c and 1^d one above another. In this case the main stream is carried from the trough 1^c to suitable chutes as shown, while the material separated, to wit, the slate is deposited in side troughs 22^b which are reversely inclined so as to carry the slate from the trough 1^c to the upper end of the trough 1^d, whereon it is subjected to a separation for the purpose of releasing any coal which may have been carried out of the main stream with the slate by the trough 1^c.

In conclusion, I wish it to be understood that while each trough is shown to be longitudinally inclined, and each section thereof inclined transversely, the longitudinal inclination is not absolutely essential, since the passage of the main stream may be effected either by gravity as here contemplated, or by any other instrumentality, so far as the invention in its broader aspects is concerned. The only thing essentially demanded by the principle of operation is that the materials shall be separated by reason of their frictional differences or their different angles of repose through the medium of a separating surface or floor, resisting the withdrawal from the stream of that portion of the material having the

least angle of repose, and permitting the withdrawal of that portion having an angle of repose sufficiently great. It should also be understood that while the illustrated embodiments of the invention are thought at this time to be preferable, I reserve the right to effect such changes, modifications, and variations of the illustrated structures as may come fairly within the scope of the protection prayed.

Having thus described my invention, what I claim as new and desire to secure by Letters-Patent is:—

1. A separating apparatus including a pair of endless floors oppositely inclined to form a trough, and having their inner edges overlapped, the adjacent portions of such floors being in proximity, presenting a substantially continuous surface, and supporting and simultaneously acting upon a given body of material passing thereover. 85

2. A separating apparatus including a pair of endless floors oppositely inclined transversely and having their inner edges overlapped, the adjacent portions of such floors being in proximity, presenting a substantially continuous surface, and supporting and simultaneously acting upon a given body of material passing thereover. 90

3. A separating apparatus including a trough having oppositely inclined endless side sections and swinging supports for said sections, such sections overlapping each other at their inner edges and constituting a continuous trough with dissimilar sides arranged to travel in opposite directions. 100

4. A separating apparatus including a trough comprising endless side sections, adjustable swinging supports for effecting the vertical adjustment of the outer edges of said sections, said sections overlapping and presenting a substantially continuous surface, a portion of one side of the trough being abrupt as compared with the opposite side, and means for moving the floor sections in opposite directions. 110

5. A separating apparatus including a trough comprising a pair of transversely inclined endless side sections, said sections overlapping and presenting a substantially continuous surface, a portion of one side of the trough being abrupt as compared with the opposite side, inner and outer rollers supporting said sections, adjustable swinging supports for effecting the vertical adjustment of the outer rollers, and means for driving the rollers to effect the movement of the floor sections in opposite directions. 115

6. In a separating apparatus, a trough comprising transversely inclined, overlapping, and oppositely movable side sections, and a chute for discharging in separate streams material following parallel paths 125

through the trough, said chute comprising a portion having a cross section curved transversely and conforming substantially with the cross section of the overlapping sections, and a portion having a flat bottom extending lengthwise of the chute.

In testimony, that I claim the foregoing

as my own, I have hereto affixed my signature in the presence of two witnesses.
